Primary Examiner — Leanne Was-Englehart*(74) Attorney, Agent, or Firm* — Birch, Stewart, Kolasch & Birch, LLP(57) **CLAIM**

The ornamental design for an information terminal for ship navigation, as shown and described.

DESCRIPTION

FIG. 1 is a perspective view of an information terminal for ship navigation;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the information terminal for ship navigation in which the design is embodied that are not considered part of the claimed design.

1 Claim, 4 Drawing Sheets(56)
